UNITED STATES PATENT OFFICE.

CHARLES VICTOR THIERRY AND MICHEL THIERRY, OF PARIS, FRANCE.

ELECTRIC ZINC-FURNACE WITH INTEGRAL CONDENSER.

1,122,664.

Specification of Letters Patent. Patented Dec. 29, 1914.

Application filed May 31, 1913. Serial No. 766,992.

To all whom it may concern:

Be it known that we, CHARLES VICTOR THIERRY and MICHEL THIERRY, both citizens of the Republic of France, and residents of the city of Paris, in said Republic of France, have invented certain new and useful Improvements in Electric Zinc-Furnaces with Integral Condensers, (Case B,) of which the following is a specification.

10 This invention relates to the metallurgy of zinc, having for its object the production of zinc-fume and its subsequent condensation to liquid metal. The particular means for attaining the desired results and 15 such an elucidation of the general principles involved as may appear necessary will be concurrently described and pointed out in connection with the accompanying drawings; which denote an embodiment of the 20 invention.

Figure 1 is a transverse center section, as on the line A, and Fig. 2 is a horizontal section and plan, as along the plane B to C and thence following the plane D.

25 The furnace is particularly intended for the reduction of oxid of zinc as for instance of the commercial grades combined with carbon, in the form of coke, coal or the like, as the reagent whereby, when adequately 30 heated and if of a comparatively high grade of purity, substantially the following representative reaction ensues, namely:

35 The heat necessary for decomposing the charge is derived by direct conduction or by radiation or by both, from a "resistor", R, formed of a bed of broken carbon, interpolated between terminals, as 3, and suitably connected to a source of electric energy, indicated by the power circuit, P. In cross section, the resistor is relatively thin, with respect to its breadth, and is supported along its lower narrow edge in a sump, 4. 40 One of the vertical longitudinal sides of the resistor is preferably confined by the inner edges of the vertically extending spaced plates, as 5, which are disposed transversely to the resistor. Thus, there are provided 45 by and between the plates 5 a series of

chutes or pockets, as S, whose bottoms, 6, may be sloped downwardly toward the sump. The chamber space, H, above the resistor, inclosed by bricks, as 7, may be filled with carbon, for the purpose, say, of 55 serving as a reserve supply to replace exhausted carbon in the more active underlying zone of the resistor. The side-pockets are to be supplied with a charge-material (ZnO and C), as J, whence the reaction will 60 take place along the vertical longitudinal face, S, of the resistor. Disposed along the opposite side of the resistor are a plurality of refractory condenser tubes, as 9, open at both ends, preferably sloping downwardly 65 and away from the resistor. These tubes are to be filled with carbon, as shown. At those ends of the tubes which are farthest from the resistor is a vertical space, or filter-chamber, T, the bottom of which, 10, 70 serves as a zinc reservoir from which collected metal may, in various suitable manners, be continuously or intermittently withdrawn. The chamber, T, is intended to be more or less filled with carbon, serving 75 as a final filter for the upwardly escaping gases, and manifestly any zinc condensed therein will gravitate to the reservoir. The carbon in the condensing tubes is preferably packed so as to be in physical contact with 80 the resistor-carbon and that contained in the filter chamber. During normal operation, the temperature of the carbon in the tubes progressively diminishes from the resistor to the filter chamber, and the rate of 85 radiation therefrom may be augmented or diminished by removing or applying blanketing material, as V, in the open space, or gap, W, above the tubes, or by heating or cooling a flue, as Y, formed in that portion 90 of the furnace wall which is opposite or adjacent to the outlet ends of the tubes. In other words, if for instance the flue Y is heated, as by means of gas or electrically from a resistor, this will impart heat to 95 the filter-carbon and thence to the carbon in the condensing tubes. It will thus be clear that the difference of temperature between the resistor, that affects the reaction, and the filter-chamber can be controllably 100

maintained by applying a heating or cooling medium to the interior of the flue Y when required. The temperature between the resistor last referred to and the filter 5 carbon in the chamber T can be controlled to a certain extent by the varying of the material at V. It would also be feasible to insert terminals in the ends of the filter chamber so as to be able to utilize the filter- 10 carbon as a direct resistor whereby the interior of the filter can be heated as desired. When the reaction is in progress, the developed fume and gas, or gases, must pass directly through the hot resistor in horizontal 15 planes, thence entering and traversing the several condenser-tubes wherein the liquated fume gravitates to the trough or receptacle at the bottom of the filter chamber T, in the manner denoted by arrow 12, and the residual gases flow upwardly, as denoted by the arrow 13, through the filter chamber and finally out to the atmosphere. The freedom of gas-flow through the filtering 20 carbon, and the volume or intensity of the 25 flame if burned to CO_2 , may be conveniently controlled by a damper or slideable bricks, as 14.

The conditions and construction here described and illustrated are favorable for 30 realizing a rapid and uniform rate of reaction and high efficiency in the condensation of fume to liquid metal. Moreover, such a type of combined furnace and condenser is easy and inexpensive to build, and 35 the cost of maintenance is of nominal amount.

The invention is not to be limited by the precise lines of the drawings, as various detail modifications may be made in the design without departing from the spirit and 40 essence thereof.

We claim as our invention:

1. In an electric zinc furnace a longitudinally extending bed of carbon resistor, 45 a charging pocket or pockets disposed along one of the vertical sides of said resistor, a plurality of transversely disposed tubes, filled with carbon which are arranged along the other vertical side of said resistor and 50 a space or chamber with which the said tubes communicate.

2. In an electric zinc furnace a bed of carbon resistor along one of whose vertical sides the reaction takes place, and a system 55 of condensing tubes arranged along the other vertical face of said resistor, all of the volatilized products of the reaction being thereby caused to first pass through the interstices of said resistor and thence directly to and into the condensing tubes.

3. In an electric zinc furnace, the combination with a longitudinally extending bed of carbon resistor and a filter chamber parallel thereto, of a plurality of trans-

versely extending interposed connecting 65 condenser tubes.

4. In an electric zinc furnace, the combination with a bed of carbon resistor and a parallel filter chamber, of a plurality of interposed connecting condenser tubes filled 70 with carbon which is in physical contact with the carbon in the resistor and the filter-carbon.

5. An electric zinc furnace having a plurality of condenser tubes leading from a 75 bed of carbon resistor to the interior of a filter chamber, and provided with an open space or gap above the said tubes from whence the rate of heat-radiation may be regulated or controlled.

6. In an electric zinc furnace a bed of carbon resistor, a filter chamber provided therein with filter carbon, a plurality of carbon-filled condenser tubes for receiving the fume from the carbon resistor, said 85 tubes communicating with the interior of the filter chambers and means for heating or cooling the carbon contained in said filter chamber.

7. In a combined zinc furnace and condenser a longitudinally extending reaction chamber provided therein with a resistor, a series of transversely extending condensing tubes and a longitudinally extending filter chamber, the condenser tubes being interposed between the resistor and the filter, said resistor being formed of broken carbon, the filter chamber being provided 95 therein with broken carbon and the condenser tubes being filled with carbon which 100 contacts at one end of each of the tubes with the resistor carbon and at the other end of each of the tubes with the filter carbon.

8. In a combined zinc furnace and condenser a longitudinally extending carbon 105 resistor, a longitudinally extending carbon filter medium, and interposed therebetween a series of transversely extending connecting condensing tubes provided therein with carbon.

9. In a zinc furnace a longitudinally extending resistor arranged so as to receive along one face thereof the charge, there being located at the opposite face thereof a system of condensing tubes which is filled 115 with broken carbon which contacts with the resistor and also with the broken carbon in a filter chamber of the furnace whereby the gaseous products of the reaction pass through the resistor, the metallic fumes being principally condensed to liquid zinc in the system of condensing tubes and the residual products passing from the condensing system through the carbon in the filter prior to escaping to the atmosphere.

10. A furnace having a longitudinally extending carbon resistor in a reaction chamber, a longitudinally extending filter chamber, a

series of transversely extending condensing tubes leading from the resistor to the interior of the filter chamber and means located adjacent to the ends of the condenser tubes for controlling the chamber temperature, the condenser tubes and the filter chamber being provided with carbon.

This specification signed and witnessed

this 5th day of May A. D. 1913, in the city of Paris, in the Republic of France. 10
